CLAIM

The ornamental design for an AC joint pad, as shown and described.

DESCRIPTION

FIG. 1 is a perspective view of a first embodiment of an AC joint pad.

FIG. 2 is a perspective view of the AC joint pad of FIG. 1.

FIG. 3 is a top view of the AC joint pad of FIG. 1.

FIG. 4 is a bottom view of the AC joint pad of FIG. 1.

FIG. 5 is a side view of the AC joint pad of FIG. 1.

FIG. 6 is a side view of the AC joint pad of FIG. 1.

FIG. 7 is a front view of the AC joint pad of FIG. 1.

FIG. 8 is a back view of the AC joint pad of FIG. 1.

FIG. 9 is a perspective view of a second embodiment of an AC joint pad.

FIG. 10 is a perspective view of the AC joint pad of FIG. 9.

FIG. 11 is a top view of the AC joint pad of FIG. 9.

FIG. 12 is a bottom view of the AC joint pad of FIG. 9.

FIG. 13 is a side view of the AC joint pad of FIG. 9.

FIG. 14 is a side view of the AC joint pad of FIG. 9.

FIG. 15 is a front view of the AC joint pad of FIG. 9.

FIG. 16 is a back view of the AC joint pad of FIG. 9.

FIG. 17 is a perspective view of a third embodiment of an AC joint pad.

FIG. 18 is a perspective view of the AC joint pad of FIG. 17.

FIG. 19 is a top view of the AC joint pad of FIG. 17.

FIG. 20 is a bottom view of the AC joint pad of FIG. 17.

FIG. 21 is a side view of the AC joint pad of FIG. 17.

FIG. 22 is a side view of the AC joint pad of FIG. 17.

FIG. 23 is a front view of the AC joint pad of FIG. 17.

(Continued)

FIG. 24 is a back view of the AC joint pad of FIG. 17. FIG. 25 is a perspective view of a fourth embodiment of an AC joint pad. FIG. 26 is a perspective view of the AC joint pad of FIG. 25. FIG. 27 is a top view of the AC joint pad of FIG. 25. FIG. 28 is a bottom view of the AC joint pad of FIG. 25. FIG. 29 is a side view of the AC joint pad of FIG. 25. FIG. 30 is a side view of the AC joint pad of FIG. 25. FIG. 31 is a front view of the AC joint pad of FIG. 25. FIG. 32 is a back view of the AC joint pad of FIG. 25. FIG. 33 is a perspective view of a fifth embodiment of an AC joint pad. FIG. 34 is a perspective view of the AC joint pad of FIG. 33. FIG. 35 is a top view of the AC joint pad of FIG. 33. FIG. 36 is a bottom view of the AC joint pad of FIG. 33. FIG. 37 is a side view of the AC joint pad of FIG. 33. FIG. 38 is a side view of the AC joint pad of FIG. 33. FIG. 39 is a front view of the AC joint pad of FIG. 33. FIG. 40 is a back view of the AC joint pad of FIG. 33. FIG. 41 is a perspective view of a sixth embodiment of an AC joint pad. FIG. 42 is a perspective view of the AC joint pad of FIG. 41. FIG. 43 is a top view of the AC joint pad of FIG. 41. FIG. 44 is a bottom view of the AC joint pad of FIG. 41. FIG. 45 is a side view of the AC joint pad of FIG. 41. FIG. 46 is a side view of the AC joint pad of FIG. 41. FIG. 47 is a front view of the AC joint pad of FIG. 41. FIG. 48 is a back view of the AC joint pad of FIG. 41. FIG. 49 is a perspective view of a seventh embodiment of an AC joint pad. FIG. 50 is a perspective view of an exemplary AC joint pad. FIG. 51 is a top view of an exemplary AC joint pad. FIG. 52 is a bottom view of the AC joint pad of FIG. 49. FIG. 53 is a side view of the AC joint pad of FIG. 49. FIG. 54 is a side view of the AC joint pad of FIG. 49. FIG. 55 is a front view of the AC joint pad of FIG. 49; and, FIG. 56 is a back view of the AC joint pad of FIG. 49. The broken lines shown in the drawings illustrate portions of the AC joint pad that form no part of the claimed design.
